UNITED STATES PATENT OFFICE.

ALLEVER BURTON SEABORNE, OF NORTH FINCHLEY, LONDON, ENGLAND.

PRIMING AND REGULATING DEVICE FOR PUMPS OF THE SCREW, CENTRIFUGAL, AND VALVELESS TYPE.

Application filed October 4, 1924. Serial No. 741,686.

To all whom it may concern:

Be it known that I, ALLEVER BURTON SEABORNE, a subject of the King of Great Britain, residing at "Eastwood", Ballard's 5 Lane, North Finchley, London, England, have invented improvements in and relating to priming and regulating devices for pumps of the screw, centrifugal, and valveless type, of which the following is a specification.

This invention relates to priming and regulating devices for screw and centrifugal and more especially for all valveless types of pumps and has for its object ensuring 15 such non-positive acting pumps always starting up and continuing in operation.

In such types of pumps, great difficulty is experienced not only in keeping them primed to facilitate starting up and continuing in operation, but when used for certain purposes a further difficulty arises in the event of the end of the suction pipe being uncovered, so allowing great quantities of air being pumped which quickly has disastrous results on the pump.

In order to overcome these defects it has been proposed to employ interceptor tanks to ensure efficient priming and to employ means for stopping the pump as soon as it 30 starts pumping air. In the case of pumps electrically driven it has been usual to employ means for automatically switching off the current to the motor but it has been difficult to arrange automatic means for 35 stopping pumps not electrically driven.

Now the present invention overcomes these drawbacks in a simple and efficient manner and allows the pump to continue functioning in a normal way even though 40 the end of the suction pipe is uncovered freely to the atmosphere.

The present invention comprises essentially means for keeping the pump always 45 full of water and only passing air through it in small and controlled quantities.

This invention will be now more particularly described making reference to the accompanying drawing in which the figure is a view in side elevation—partly in section—of the preferred embodiment of the 50 present invention.

A closed tank *a* is connected at its lower part to the inlet *b* of the pump *c*, which is situated below said tank *a*, and at its upper

part is connected to the suction pipe *d*. 55 Within the tank *a* is a conical member *e*, together with a float *f* adapted to control the opening and closing of any suitable type of valve *g* contained in a casing in communication with the suction pipe *d* where 60 it enters the tank *a* and with a pipe or passage *h* communicating either with a reservoir or tank *i* into which the liquid is pumped through the main *k* or with an independent liquid supply. The member *e* is a 65 coned tube, shaped and arranged as shown,—the bore of which is in line with the entrance to the tank *a* from the suction pipe *d* and the exit from the tank *a* to the inlet pipe *b* of the pump *c*. The upper end of this tube 70 *e* terminates some distance below the said entrance to the tank *a* and its bottom end is in close proximity to said exit from the tank, by such means it will be seen that any 75 relatively large pieces of foreign matter are 80 prevented from entering the suction pipe *b* of the pump. The tube *e* is held in proper position within the tank *a* by webs or a spider as shown. The whole arrangement 85 being such that in normal operation all liquid passes through the closed tank *a* before entering the pump *c* and any air contained in the liquid and accumulating in the upper part of the tank is removed together 90 with the liquid through the pump *c*. If, 85 however, the liquid falls below the end of the suction pipe *d* so as to uncover it to the atmosphere, the level of liquid falls in the closed tank *a* and with it the float *f*, which then operates the valve *g* to allow 95 liquid to enter the closed tank *a* from the reservoir *i* or other supply. This operation goes on continuously, whilst the suction pipe *d* is uncovered, the liquid being pumped in a closed circuit entraining air 95 from the suction pipe *d* and passing it with the liquid through the pump *c* and back into the reservoir *i*.

When the liquid rises to close the end of the suction pipe *d* it is still pumped in a closed circuit until it has created sufficient negative pressure in the closed tank *a* as to cause the liquid to rise in the suction pipe *d* and thus into the closed tank *a*.

The level in the closed tank *a* will continue to rise until the float *f* therein rises and operates to close the valve *g*, so cutting off the liquid supply therethrough and so

establishing the normal operation of the pump.

It is preferable to employ the reservoir *i* as the source of supply of liquid to the closed tank *a* through the valve *g*.

In a preferred construction as shown, the closed tank *a* is formed in two parts, the one containing the coned tube *e* and the other forming the float chamber and the two communicating through a gauze screen or strainer *a¹* so as to ensure the float *f* working in a liquid freed from solid matter or débris and with the same object in view the liquid supply to the valve *g* may be also constrained 15 to pass through a suitably arranged strainer.

I declare that what I claim and desire to secure by Letters Patent is:—

1. A priming and regulating device for pumps of the centrifugal and valveless type 20 comprising a closed tank between the suction pipe and the pump, a connection between the lower part of the tank and the inlet of the pump which is situated below said tank, a connection between the upper 25 part of the tank and the suction pipe, a coned

tube within said tank, a passage connecting together the suction pipe where it enters the tank and a reservoir into which the liquid is pumped, a valve situated in said passage and a float within said tank adapted to control the opening and closing of said valve, as set forth. 30

2. A priming and regulating device for pumps of the centrifugal and valveless type 35 comprising a closed tank between the suction pipe and the pump, a connection between the lower part of the tank and the inlet of the pump which is situated below said tank, a connection between the upper part of the tank and the suction pipe, a coned tube within said tank, a passage connecting together the suction pipe where it enters the tank and a reservoir into which the liquid is pumped, a valve situated in said pipe or passage, a float within said tank 40 adapted to control the opening and closing of said valve and straining device to ensure the float and valve working in a liquid freed from solid matter, as set forth. 45
